UNITED STATES PATENT OFFICE.

CHAUNCEY P. FULLER, OF BELLE VERNON, PENNSYLVANIA.

ROLLING MILL.

Application filed October 28, 1920. Serial No. 418,965.

To all whom it may concern:

Be it known that I, CHAUNCEY P. FULLER, a citizen of the United States, and a resident of Belle Vernon, in the county 5 of Fayette and State of Pennsylvania, have invented a new and useful Improvement in Rolling Mills, of which the following is a specification.

This invention relates to cross rolling mills for use in the manufacture of seamless tubes, and while particularly designed for rolling hollow billets to the desired wall thickness, it is also adapted, by modification of the rolls for piercing a solid billet, and 15 in fact for producing a finished tube from a solid billet. It may also be used for reducing the diameter of the tube without reducing its wall thickness.

The primary object of the invention is to 20 provide a cross rolling mill for producing finished tubes from hollow or solid billets in the one machine.

A further object is to provide a cross rolling mill which will, first, produce tubes that 25 are smoother, straighter and more regular, with less relative expansion of diameter and less tendency to wall eccentricity than can be produced on existing cross rolling mills or on grooved rolling mills without the subsequent use of reeling machines; and, second, to produce tubes more expeditiously, and with better power efficiency than has heretofore been possible with cross rolling mills, or with combinations of grooved rolling mills and reeling machines. Other objects and advantages of the invention will 30 be apparent from the detailed description following.

In the accompanying drawings Fig. 1 is 35 an end view of the mill, a portion being broken away to more clearly show the structure; Fig. 2 is a vertical section taken on the line 2—2, Fig. 1, Fig. 3 is a plan view of the mill; Fig. 4 is a plan view and Fig. 40 5 a side view showing the rolls in their relations to each other and to the mandrel; Fig. 6 is a transverse central section through the rolls, showing a tube in the pass of the rolls; Fig. 7 is a detailed view of one form 45 of roll and mandrel, shown in their oblique relation to each other and indicating the nature of contact between the roll and the billet, and also showing the changes effected on the tube wall between the roll and the 50 mandrel; and Fig. 8 shows a rectilinear development of the line of contact $\alpha-g$ be-

tween a roll and the billet in relation to the mandrel.

In the drawing 1, 1 represent bed plates or mill shoes, secured to the foundation and serving as the support for the mill. 2 represents an annular frame which in radial cross section at any point is substantially H-shaped, having an outer annular flanged portion 2^a, an inner annular flanged portion 2^b, and the connecting web portion 2^c, which is cut away at points for mounting therein suitable gears as hereinafter described. This annular frame is provided with projections or feet 3 which are secured to the 70 shoes 1 by suitable bolts as shown.

The rolls 4 have the usual necks or journals 5 carried in the bearing boxes 6, which constitute the ends of the roll carriers 7. Each roll carrier is provided with an outward radial projection, of cylindrical shape 8, having therein a tapered socket into which the tapered end 9 of adjusting screw 10 is forced by the heavy bolt 11 extending axially through the adjusting screw and 75 into the roll carrier, as shown in Fig. 2. By this construction the adjusting screw is made virtually integral with the roll carrier, and serves as an outboard support to steady the roll carrier. 85

The projection 8 is slidable but non-rotatably secured, by means of key 12, in the cylindrical sleeve 13, which is mounted in the inner annular flanged portion 2^b of the main frame. The sleeve 13 is provided with a 90 square flange 14, which is engaged by two wedge keys 15 and is thereby held from turning. The obliquity or feed angle of the rolls is thus maintained, and can be varied by replacing keys 15 with other keys of different taper. 95

Each adjusting screw 10 is engaged by a threaded nut 17 which is rotatably mounted between bearing rings 18 located between the outer and inner annular portions 2^a and 2^b of the main frame. These nuts 17 are provided on their peripheries with bevel gear teeth and are engaged by a bevel ring-gear 19 carried on six (or more) roller-bearing spools, 20, which serve as an efficient journal upon which the ring gear may turn. The ring-gear 19 is held on said spools against displacement by the retaining ring 21. 105

The ring-gear 19 is driven by a bevel gear 22 fixed on a shaft 23, which is mounted radially in suitable bearings in the frame 110

members 2^a and 2^b, and has secured thereto at its outer end a worm wheel 25 engaged by a worm 26 on a shaft 27. Shaft 27 is shown provided with an operating hand wheel 28, but may obviously be operated by any other suitable means, such as by an electric motor or a hydraulic rack and pinion. By the means described all three rolls can be easily adjusted simultaneously and 10 equally toward or away from the pass of the tube, as required for rolling tubes of various sizes, without affecting their obliquity or feed angles.

One of the necks of each roll is provided 15 with a suitable extension, such as that shown at 29, for having connected thereto a suitable driving means, which may be of any of the well known types now used for driving cross or skew rolls. The driving means will 20 be arranged to drive all three rolls at the same speed.

30 indicates the mandrel or plug lying in the pass of the rolls and held in position by the usual mandrel bar 31 which will be 25 mounted for withdrawal from the roll pass in a manner well understood by those skilled in the art.

In the mill described, the three rolls are 30 identical as to shape and size, and all are positively driven at equal speeds. Corresponding points on each roll are all equidistant from the axis of the tube pass, and 35 form the vertices of an equilateral triangle. The three planes in which lie the respective roll axes form the three faces of an equilateral triangular prism; and equal angles are formed between each roll axis and the intersections of its respective plane with the planes of the two other roll axes. The angles 40 thus measured will always be less than 45°. As described, this angle may be varied, but the condition of equality of angularity with respect to all three rolls will always be maintained. A section through the mill transversely to the pass line at any point will 45 show the peripheries of the three rolls as equal ellipses.

In consequence of the geometrical conditions just described, the actions of the three 50 rolls upon the billet are identical, the rolls themselves forming the guides for the billet passing through the mill, and sliding or friction guides being entirely eliminated. Furthermore, the billet is acted upon at 55 three points spaced 120° apart around its periphery, with the result that the tube is constrained against increase in diameter to a greater extent than with cross rolling mills having but two rolls.

60 The contour of the rolls may be varied, but for rerolling a hollow billet it is preferred to use rolls which are approximately hyperboloids of revolution, as illustrated in Fig. 7. Rolls of this contour have a rolling 65 contact with the surface of the billet along

an approximate helical element of considerable length, a projection of this line of contact being shown in Fig. 7 by the line e—g. This long contact results in forming smooth, substantially straight tubes. The hollow 70

billet to be rolled comes into contact with the three rolls simultaneously at the points f (see Fig. 8) and is then pinched inwardly, that is reduced in diameter, entering the feeding-in pass e—a, which serves to grip 75 the billet and force it into the reducing pass a—b. At a begins the reduction of the wall of the billet to the form shown in Fig. 8. From b the contact of the rolls is parallel to the mandrel and is of very considerable 80 length, thus giving a true reeling action which smoothes the tube both inside and out. The tube being compressed between the rolls and the mandrel at three equalized distances around the periphery, when it 85 leaves the parallel pass at g has a cross section which may be likened to a clover leaf, as shown in Fig. 6. Due to the progressive rolling of the tube, this form cannot persist, but changes to a substantially true circular 90

form as soon as the tube is free from the rolls. To prevent this transition from resulting in a spiral marking on the tube, it is controlled by rounding the profile of the exit end of the rolls to a radius as shown at 95 r, Figs. 7 and 8.

The result of rolling a hollow billet on rolls of the character described is a tube which is smooth both inside and outside, is uniform and substantially circular in 100 cross-section, and is not bent, scored, or grooved as are tubes produced by the usual method in so-called plug rolls. Furthermore, the reeling or smoothing is effected in the same mill in which the reduction of wall thickness is effected, whereby is produced in one machine a finished tube, requiring no further operation other than passing the same through the usual sizing rolls to gauge 105 it to the exact diameter required.

110 As compared with prior cross rolling mills, the described mill has the following peculiar characteristics:— No guides are required (except a bell-mouth inlet) since the work is constrained and guided by the rolls along three equi-spaced helices; the resultants of all working forces are concurrent in the center line, or else are symmetrical about the center line, and therefore all forces are balanced except the necessary rolling and feeding components; since all three rolls are driven (at equal speed) there is no pushing or pulling of the metal over a guide or friction roll; the provision of three helical lines of long contact, instead of two, permits the use of very large feed angles without sacrifice of smoothness, thus combining to a considerable extent the action of grooved rolls and cross rolls; the provision of three driven rolls reduces slip, which results in higher 115 120 125 130

speed through the mill; constraining the tube radially at three points instead of two results in less expansion of diameter and greater increase of length, for the same reduction of wall thickness; the absence of frictional guides, and the fact that all forces are concurrent or symmetrical result in more efficient utilization of the power; and, finally, the provision of hyperboloid rolls having contact with the billet for a great length along three twisted lines or approximate helices produces tubes that are smooth, straight, and regular.

In addition to the foregoing, the mill illustrated and described is of simple construction; the design permits of rugged proportioning of all parts; all adjustments are simple and easily made; and since this mill embodies the functions not only of a rolling mill, but also those of a reeler, there is a great saving in floor space, size of crew, investment, and power required in the rolling of seamless tubes.

The invention is not limited to the contour of the rolls illustrated, as this may be varied as found expedient in practice. The form illustrated however is well designed for producing smooth regular tubes from hollow billets.

For reducing the diameter of a tube without reducing its wall thickness, the mandrel 30 may be omitted.

I claim:

1. In a rolling mill the combination of three power driven cross rolls identical in shape and size, set at three uniform intervals around a central pass and at equal distances radially therefrom, and with their axes making angles greater than 45° to a plane normal to the pass axis, and having equal angles of obliquity to said pass, means for bodily adjusting all said rolls equally toward and from the pass without altering their obliquity, each roll being approximately a hyperboloid of revolution.

2. In a rolling mill the combination of three power driven cross rolls identical in shape and size, set at three uniform intervals around a central pass and at equal distances radially therefrom, and having equal angles of obliquity to said pass, and means for bodily adjusting all three of said rolls equally toward and away from the axis of the pass without altering their obliquity to the pass.

3. In a tube rolling mill the combination of three power driven cross rolls identical in shape and size, set at three uniform intervals around a central pass and at equal distances radially therefrom, and having equal angles of obliquity to said pass, in combination with a plug or mandrel lying in the pass, said rolls and mandrel having contours to form, first, a gripping or feeding-in pass between the rolls, second, a wall

reducing pass between the rolls and the mandrel, and, third, a parallel reeling pass between the rolls and mandrel.

4. In a tube rolling mill the combination of three power driven cross rolls identical in shape and size, set at three uniform intervals around a central pass and at equal distances radially therefrom, and having equal angles of obliquity to said pass, in combination with a plug or mandrel lying in the pass, said rolls and mandrel having contours to form, first, a gripping or feeding-in pass between the rolls, second, a wall reducing pass between the rolls and the mandrel, third, a parallel reeling pass between the rolls and mandrel, and, fourth, a gradually diverging exit or rounding-up pass between the rolls.

5. In a rolling mill the combination of three power driven cross rolls identical in shape and size, set at three uniform intervals around a central pass and at equal distances radially therefrom, and having equal angles of obliquity to said pass, means for radially adjusting all three of said rolls equally toward and away from the axis of the pass, and means for maintaining equal the obliquity of each of the three rolls with respect to the pass, the means for radially adjusting the rolls and the said maintaining means being independent of each other.

6. In a rolling mill the combination of three power driven cross rolls identical in shape and size, set at three uniform intervals around a central pass and at equal distances radially therefrom, and having equal angles of obliquity to said pass, each roll being mounted to have a swivel movement about a normal axis substantially midway of the length of its working face, whereby its obliquity to the pass can be varied, and means for maintaining equal the obliquity of each of the three rolls with respect to the pass.

7. In a rolling mill the combination of three power driven cross rolls identical in shape and size, set at three uniform intervals around a central pass and at equal distances radially therefrom, and having equal angles of obliquity to said pass, each roll being approximately a hyperboloid of revolution, each roll being mounted to have a swivel movement about a normal axis substantially midway of the length of its working face, whereby its obliquity to the pass can be varied, and means for maintaining equal the obliquity of each of the three rolls with respect to the pass.

8. In a rolling mill the combination of three power driven cross rolls identical in shape and size, set at three uniform intervals around a central pass and at equal distances radially therefrom, and having equal angles of obliquity to said pass, each roll being mounted to have a swivel move-

ment about a normal axis substantially midway of the length of its working face, whereby its obliquity to the pass can be varied, means for maintaining equal the obliquity of each of the three rolls with respect to the pass, and means for bodily adjusting the three rolls equally toward or away from the axis of the pass.

9. In a rolling mill the combination of 10 three power driven cross rolls identical in shape and size, set at three uniform intervals around a central pass and at equal distances radially therefrom, and having equal angles of obliquity to said pass, each 15 roll being mounted to have a swivelling

movement about a normal axis substantially midway of the length of its working face, whereby its obliquity to the pass may be varied, means for retaining the rolls against swivelling movement, and means 20 for bodily adjusting the three rolls equally toward or away from the axis of the pass, said retaining means and adjusting means being independent of each other.

In testimony whereof, I have hereunto set 25 my hand.

CHAUNCEY P. FULLER.
